UNITED STATES PATENT OFFICE.

GEORGE B. FOWLER, OF BROOKLYN, ASSIGNOR OF ONE-HALF TO ERNEST H. SEEMANN, OF NEW YORK, N. Y.

PICTURE CORD AND HOOK HANGER.

SPECIFICATION forming part of Letters Patent No. 357,312, dated February 8, 1887.

Application filed October 23, 1886. Serial No. 217,002. (No model.)

To all whom it may concern:

Be it known that I, GEORGE B. FOWLER, a citizen of the United States, residing at Brooklyn, in the county of Kings and State of New York, have invented a certain new and Improved Combination Picture Cord and Hook Hanger, of which the following is a full, clear, and exact specification.

My invention relates to a household implement in which is presented a combination of devices whereby it is made to serve a number of purposes, all of these purposes being independent of each other; and it consists, first, in providing the body of the implement, which is formed to open or turn the gas-pipe key of a chandelier, &c., with means for hanging picture-hooks, picture-frames and their cords in elevated positions and adjusting them close to the wall; and, secondly, in providing the said implement with means for lowering and raising a window-sash; and, finally, in other minor details of construction, which will be more fully hereinafter set forth.

In the accompanying drawings, which clearly illustrate my invention, Figure 1 is a perspective view of my combination implement. Fig. 2 is a side elevation, and Fig. 3 is a side view showing the spring clamping device with engaged picture-hook.

Let A represent a straight rod or shank, serving as the handle of the implement, and which may be composed of two or more sections adapted to be fitted one within the other, as shown in Fig. 2, so that the handle may be increased in length as occasion may require.

B is a ferrule on the upper end of the handle A, and C a gas-key turner or clamp composed of the two jaws D D', having a wedge-shaped opening to receive the key. One of these jaws, D', is projected upward a considerable distance above the other, and its extreme edge is turned outwardly and inclining downwardly to form the inclined lip or flange E.

This prolonged jaw, with the projecting flange, is made to serve an independent purpose—viz., that of pushing up a window-sash, or of forcing back on the body of a picture-nail the hanging-cord, when by inadvertence it

has been drawn away from the wall. In both 50 of these cases, as well as all others where my implement is specially applicable, the object to be adjusted is beyond the stretch of the hand, and could only be reached by mounting on an elevation.

A second object is to provide means for holding a picture-hook while it is being carried up and adjusted over the elevated molding which surrounds the wall of the room, and to accomplish this I provide in the central 60 part of the lip or flange a recess, F, which is made large enough to hold the largest size of hook as well as the smallest.

G are spring-arms, between which the hook is clamped, as seen in Fig. 3. This 55 spring is preferably formed out of a single length of wire secured around pins H H, projecting from the elongated jaw D', the free ends of the wire being bent upward and their extremity turned over and inward, as shown 70 at I, to form clamp-arms to embrace the hook. As seen in Fig. 3, the hook I' is placed in the recess in the lip and held between the spring-arms in the proper upright position to enable 75 it to be hooked over the molding, which is done by raising the implement and engaging the hook over the same, when by a slight pull downward the hook will be released from the spring. This forms a second feature of my combination.

From the shorter jaw, D, of the main body of the implement projects upwardly a wire, J, which is bent to approximate somewhat the shape of the letter S, and so as to form a hook end, K. The purpose of this hook is to permit the holding of a picture-cord in order to raise the attached picture and suspend it from a nail in the upper part of the wall. When accomplishing this the flange E will be brought into requisition to push the cord back against 90 the wall. This is one of the essential features of my combination.

On the under side of the hook end K is provided a lug, T, which has its under surface serrated or roughened, so as to enable it to bite 95 or take hold of the article with which it is brought into contact. The purpose of this latter device is to afford a means of drawing

down a window-sash, which is accomplished by bringing the lug into contact therewith and pulling downward. The above several devices, as shown in the combination, may vary slightly in general form and construction without materially affecting the nature of my combined implement; and what I claim, and desire to secure by Letters Patent, is—

The combination implement herein described, comprising the handle A, having jaws D D', with flange E, clamping device G, hook K, and lug T, all arranged as and for the purposes set forth.

GEORGE B. FOWLER.
